UNITED STATES PATENT OFFICE.

JOHN WRIGHT SEAVER, OF CLEVELAND, OHIO, ASSIGNOR, BY MESNE ASSIGNMENTS, TO THE WELLMAN-SEAVER-MORGAN COMPANY, OF CLEVELAND, OHIO, A CORPORATION OF OHIO.

GRAB-BUCKET.

SPECIFICATION forming part of Letters Patent No. 747,783, dated December 22, 1903.

Application filed March 13, 1903. Serial No. 147,669. (No model.)

To all whom it may concern:

Be it known that I, JOHN WRIGHT SEAVER, a citizen of the United States, and a resident of Cleveland, Ohio, have invented certain improvements in Grab-Buckets, of which the following is a specification.

The object of my invention is to so construct a grab-bucket as to provide for the opening and closing of the same by means of a more acceptable character than those heretofore used in this class of devices. This object I attain in the manner hereinafter set forth, reference being had to the accompanying drawings, in which—

15 Figure 1 is a side view of a grab-bucket constructed in accordance with my invention, together with a crane for carrying the same and mechanism for raising and lowering the bucket and for traversing it on said crane.

20 Fig. 2 is a side view of the bucket on a larger scale. Fig. 3 is an end view of the bucket and its operating mechanism, the case containing the latter being broken away in order to illustrate such mechanism; and Fig. 4 is a 25 transverse section through said casing.

A represents the bridge of a traveling crane, mounted by means of suitable rollers *a* upon runways *a'*, and upon this crane-bridge is mounted, so as to traverse from end to end 30 of the same, a trolley *D*, and at one end of the bridge are a pair of winding-drums *B* and *C* and an electric or other motor *H*, which can be caused to operate either or both of the drums *B* and *C*.

35 The drum *B* receives the hoisting-rope *E*, which passes around a suitable sheave or sheaves on the trolley *D*, and the drum *C* receives the rope *F*, whereby the traversing is effected, this rope passing around a sheave 40 *G* at the opposite end of the bridge.

In the present instance the bucket is of the clam-shell type and comprises two halves *L* *L'*, which are mounted, by means of pivoted and swinging arms *J* *J'* and *K* *K'*, upon a box or 45 casing *I* above the bucket, this box or casing, as well as the bucket, being suspended from the trolley *D* by means of a rope *E*, so that it can be readily raised and lowered, as well as traversed to and fro with the trolley. Each 50 half of the bucket has at each side an arm *J*

or *J'* and an arm *K* or *K'*, connected to the bucket at different points, and these arms may be so proportioned as to length and their pivots may be so disposed as to give any desired tipping or tilting movement to each half 55 of the bucket as it is swung outward. In the present instance the arms *K* *K'* are somewhat longer than the arms *J* *J'* and are pivoted to the casing at a higher point. The arms *J* *J'* are carried by the opposite ends of shafts 60 *O* *O'*, which pass through the casing *I* and through openings in the ends of the same, which openings may, if desired, be provided with suitable dust-proof bearing-boxes, the arms *J* *J'* being preferably contained within 65 hoods *I'* on the outside of the casing *I*.

An electric motor *M* is located between and suitably mounted upon the shafts *O* *O'*, and motion like in extent, but reverse in direction is imparted to said shafts from the motor 70 by any suitable system of gearing. In the present instance this system of gearing comprises a pinion *N* on the motor-shaft, which pinion meshes with a spur-wheel *N'*, turning loosely on the shaft *O'* and having any suitable form of frictional connection with a pinion *N*², likewise loosely mounted on said shaft *O'*, said pinion *N*² meshing with a spur-wheel *N*³, which is secured to the shaft *O* and to a pinion *N*⁴, which meshes with a spur-wheel 75 *N*⁵, secured to the shaft *O*. While this arrangement of gearing serves to positively swing the arms *J* *J'* from and toward each other, further connection between said arms is provided by intermeshing toothed segments *S* *S'*, carried by the shafts *O* *O'*, respectively, as shown by dotted lines in Fig. 2: 80

In order to prevent excessive lift of the opposite halves of the bucket and also to prevent strain upon the parts when the two 85 halves of the bucket have been closed together, automatic cut-outs *P* *P'* are provided on the casing *I*, one of these cut-outs being struck and operated by one of the arms *J* when the latter has reached the limit of its 90 downward movement and the other being struck and operated by said arm *J* when it has reached the limit of its upward movement.

The electric motor employed is one whose direction of movement is reversible, the cut- 95

out P operating to arrest the movement when the motor is running in one direction and the cut-out P' operating to arrest the movement of the motor when it is running in the opposite direction.

Current is conveyed to the motor from the trolley D through a cable Q, which is wound upon a drum R on the trolley, this drum having a normal tendency to wind up the cable. Q as the bucket is raised, but permitting the unwinding of the cable as the bucket is lowered.

The mechanism described is a simpler and more effective means of opening and closing the buckets than the usual arrangements of ropes, levers, and sheaves or pulleys, and the weight of the motor and its appurtenances is in many cases an advantage, since this added weight causes the bucket to better dig into masses of ore or other material which are difficult to penetrate.

While I have described and prefer to use a bucket composed of two swinging halves, as shown, it will be evident that my invention is not limited in this respect, but can be applied to other forms of bucket as well.

In case the two halves of the bucket in opening or closing meet with obstruction which is too difficult to overcome the connection between the spur-wheel N' and pinion N² will yield and prevent injury to the motor, the gearing, or other parts of the apparatus.

Having thus described my invention, I claim and desire to secure by Letters Patent—

1. The combination of the movable element of a bucket, a hanger on which the same is mounted, a motor carried by said hanger, mechanism whereby said motor is caused to actuate the movable element of the bucket, a crane-trolley from which said bucket-hanger is suspended so as to be raised and lowered, and a flexible conductor extending from the crane-trolley to the bucket-hanger, substantially as specified.

2. The combination of the movable element of a bucket, a hanger upon which the same is mounted, an electric motor carried by said hanger, mechanism whereby the movement of said motor is caused to actuate the movable element of the bucket, and electric cut-outs operating to arrest the movement of the motor when the parts reach either of their extreme positions, substantially as specified. 50

3. The combination of the two halves of a bucket, of the clam-shell type, arms carrying the said halves of the bucket, shafts for said arms, a hanger in which said shafts are mounted, a motor carried by said hanger, and gearing whereby said motor is caused to move one 55 of said shafts in one direction and the other in the opposite direction, substantially as specified.

4. The combination of the two halves of a bucket of the clam-shell type, arms carrying 60 the halves of said bucket, shafts for said arms, a hanger in which said shafts are mounted, a motor also carried by said hanger, gearing whereby said motor is caused to rock said shafts in opposite directions, and intermeshing toothed segments connecting said shafts, 70 substantially as specified.

5. The combination of the two halves of a bucket of the clam-shell type, arms carrying 75 the halves of the bucket, shafts for said arms, a hanger in which said shafts are mounted, a motor also carried by said hanger, gearing whereby said motor is caused to rock said shaft in opposite directions, and other arms connected to the halves of the bucket and 80 pivoted eccentrically in respect to the rock-shafts, substantially as specified.

In testimony whereof I have signed my name to this specification in the presence of two subscribing witnesses.

JOHN WRIGHT SEAVER.
